UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC TRAIN-LINE SWITCH.

Application filed March 19, 1924. Serial No. 700,212.

This invention relates to a switch mechanism for controlling electric train line circuits in electric train service.

The principal object of my invention is to provide an improved switch mechanism of the above character.

In the accompanying drawing; Fig. 1 is a diagrammatic view of a train line controlling switch apparatus embodying my invention; Fig. 2 a plan view of the pneumatic switch mechanism shown in Fig. 1 with the cover plate removed; Fig. 3 a section on the line 3—3 of Fig. 2; and Fig. 4 a diagram illustrating the circuit connections to the pneumatically operated switch.

It has heretofore been proposed to employ a manually operated switch mechanism for controlling the electric train line circuits on a car, when the circuits are connected between cars by the operation of an automatic train line coupler, in order that the circuits may be opened before the cars are separated, so as to prevent arcing at the contacts associated with the automatic coupler. With the above arrangement, if current is taken from the trolley wire on one car, it is carried to the other cars through a bus line which is controlled by jumpers located between the cars.

It is now proposed to control the bus line circuits by means of couplers adapted to be automatically operated by the coming together of the cars and in such case, it is desirable to provide an additional hand operated switch mechanism for opening the bus line circuits before cars are separated.

According to my invention, an additional switch mechanism is provided for controlling the bus line circuits and adapted to be operated simultaneously with the switch mechanism for controlling the other train line circuits.

As shown in Fig. 1, the reference numeral 1 indicates a switch mechanism for controlling the ordinary electric train line circuits and 2 the additional switch mechanism for controlling the bus line circuits.

The switch mechanism 1 may comprise a casing containing a rotatable switch member 3 adapted to be operated for controlling the opening and closing of a plurality of train line circuits connected to contact fingers 4. The switch member 3 is provided with an operating lever 5 and connected to

the opposite ends of said lever are rods 6 by which the member 3 may be manually operated at opposite sides of the car.

The additional switch mechanism 2 may comprise a casing in which is mounted a switch drum shaft 7. Mounted on the shaft 7 is a drum contact member having contact segments 8 and 9 and adapted to engage the segment 8 are pairs of contact fingers 10 and 11. The contact segment 9 is of greater extent than the segment 8 and adapted to engage the segment 9 is a contact finger 12.

The contact segments above referred to may control the main trolley circuit and in addition a switch segment 13 may be carried by the shaft 7 for controlling a bus line circuit, such as the circuit for supplying current to the compressor motors. Adapted to engage the segment 13 is a pair of contact fingers 14.

A cylinder 15 is formed in the casing of the switch mechanism 2 and mounted in said cylinder is a piston 16 having a piston stem 17. The outer end of the stem 17 extends into a spring chamber 18 containing a coil spring 19. Said spring engages a member 20 secured to the stem 17 and tends to move the stem toward the left.

An arm 21 is applied to the squared end of shaft 7 and said arm is forked to engage over a flattened section of the stem 17. A pin 22 extends out from opposite sides of the flattened portion of the stem and engages in slots 23 in the arm 21.

The supply of fluid under pressure for operating piston 16 is controlled by a valve 24 having an operating arm 25 which is connected to a rod 26 adapted to be operated by the movement of the lever 5. The valve 24 controls communication from a fluid pressure supply pipe 27 to a pipe 28 and controlling communication from pipe 28 to piston 16 is a valve piston 29 which is subject to the pressure of a spring 30.

In operation after cars are coupled up, one of the rods 6 extending to the side of the car is operated so as to shift the switch member 3 from the cut-out position shown in Fig. 1 to the cut-in position in which the several train line circuits are closed through the contact fingers 4. The movement of the lever 5 to effect the rotation of the switch member 3 also effects the movement of the valve 24 to a position in which port 31 connects supply

pipe 27 with pipe 28. When the pressure in pipe 28 has been raised to a predetermined degree, the valve piston 29 will be lifted from its lower seat, to establish communication from pipe 28 to piston 16, and as soon as the valve piston lifts from its seat, the full area of said valve piston is exposed to fluid pressure, so that the valve piston will be quickly moved to its upper seat. Fluid supplied to piston 16 operates to shift same to the right, so that the pin 22 is shifted to rotate the arm 21 and the drum shaft 7.

The contact segments 8, 9, and 13 are thus rotated to close the main and the compressor bus line circuits through the contact fingers 10, 11, and 14.

When cars are to be uncoupled, one of the rods 6 is operated to rotate the switch member 3 to its cut-out position, as shown in Fig. 1 and at the same time, the valve 24 is operated through the rod 26 and arm 25 to cut off communication from supply pipe 27 to pipe 28 and to open communication from pipe 28 to an atmospheric exhaust port 32. Fluid under pressure is then vented from the valve piston 29 and also from the piston 16 and when the pressure on the valve piston 29 has been reduced to a predetermined degree, the valve piston will be moved from its upper seat. Communication is then established from piston 16 and the under side of valve piston 29 through a passage 33 to a large exhaust port 34, so that a quick discharge of fluid from the piston 16 is effected. A quick movement of the piston 16 by spring 19 is thus produced, so that the switch drum segments are moved to cut-out position with a quick snap.

In the operation of shifting the switch drum to its cut-out position, the contact fingers 10 and 11 separate from the contact seg-

ment 8 while the contact finger 12 remains in contact with the segment 9, due to the contact segment 9 being more extended than the segment 8. Consequently the final opening of the circuit is at the contact finger 12. A heavy arc may form at this contact finger when separation takes place, but since the arc is concentrated at a single contact finger, the arc may be readily blown out by means of the usual arc blow-out mechanism.

Having now described my invention, what I claim as new and desire to secure by Letters Patent, is:—

1. The combination with an electric switch mechanism and a piston operated by fluid under pressure for actuating said mechanism, of means operated upon a reduction in fluid pressure on said piston for opening a communication through which fluid is vented from said piston.

2. The combination with an electric switch mechanism and a piston operated by fluid under pressure for actuating said mechanism, of a valve piston operated upon an increase in fluid pressure thereon for opening communication through which fluid is supplied to said piston.

3. The combination with an electric switch mechanism and a piston operated by fluid under pressure for actuating said mechanism, of a valve piston operated upon an increase in fluid pressure thereon for opening communication through which fluid is supplied to said piston and upon a reduction in pressure thereon for opening a communication through which fluid under pressure is vented from said piston.

In testimony whereof I have hereunto set my hand.

CLYDE C. FARMER.
